UNITED STATES PATENT OFFICE.

GEORGE W. CRISPELL, OF ALBANY, NEW YORK.

STILL.

1,231,857.

Specification of Letters Patent.

Patented July 3, 1917.

Application filed September 29, 1916. Serial No. 122,936.

To all whom it may concern:

Be it known that I, GEORGE W. CRISPELL, a citizen of the United States of America, residing at the city of Albany, in the county 5 of Albany and State of New York, have invented certain new and useful Improvements in Stills, of which the following is a specification.

My invention relates to stills, and the object of my invention is to provide a simple, inexpensive device for distilling water particularly useful for furnishing distilled water for electric batteries, and adapted to be placed in a garage and connected up with a 15 water reservoir, with means for supplying a limited amount of water which may be quickly converted into steam, condensing the steam in a lead lined chamber; together with such other elements and combinations as are 20 hereinafter more particularly set forth and claimed.

I accomplish these objects by means of the apparatus illustrated in the accompanying drawing, in which:

25 Figure 1 is a vertical section.

Fig. 2 is a plan view of my invention.

Similar letters refer to similar parts throughout the several views.

The necessity for having distilled water in 30 an electric battery is well known, but because of lack of facilities for readily obtaining it, sometimes undistilled water is used with great injury to the battery. I have invented a simple and inexpensive, but very 35 effective distilling apparatus, which will act readily because very little water is placed over the fire, and my arrangement for condensation is so convenient, works so quickly and requires so little knowledge that it can 40 be successfully operated by the most inexperienced person.

An air-tight container, A, holds the water and near the bottom is a tube, B, communicating with the steamer, C, the water 45 passing from the bottom of the container, A, to the bottom of the steamer, C. Near the upper part of the receptacle, A, I place one end of the pipe, D, the other end, d, of the pipe entering the steamer, C, above 50 the tube, B. When the water from the container, A, fills the portion, d, of the pipe, D, it shuts off the flow from the container, A, stopping the flow of air to the top of the container. When the water in the steamer, 55 C, gets below the top of the portion, d, the water will again flow into the steamer

through the tube, B, until it reaches the height of the portion, d. Thus the water is automatically furnished in sufficient quantity. The steamer, C, above that portion thereof 60 which contains the water, is provided with converging walls, E, E, extending a considerable distance above the water and then bent to form a stack-shaped portion, F, projecting into the condensing chamber, G. 65 Above the stack, F, and preferably secured to it by the straps, g, I arrange a baffle plate, H, against which the steam admitted from the stack, F, will impinge and be directed into the chamber, G, as shown by arrows in 70 Fig. 1.

The condensing chamber, G, is preferably lined with lead along the sides, top and bottom and has at one end thereof a discharge opening, J. Above the chamber, G, I arrange the cold water receptacle, K, held in position by means of suitable bands, L, L, secured to the upright posts, M, M, and also supported by the lower wall, P, of the condensing chamber which is connected with 80 the exterior wall of the cooling chamber, which wall rests upon a collar, R, around the stack, F. The posts, M, M, are secured by the bolts, O, O, or in any suitable manner, to the base of the steamer. Water may 85 be supplied to the receptacle, K, through the inlet, 1, and be discharged through the outlet, 2, although I often use the receptacle without any outlet or inlet, simply pour the water into the top of the receptacle. Beneath the steamer, C, I place a suitable burner, N.

The operation of my device is as follows:

The water having been placed in the container, A, and filling the bottom of the 95 steamer, C, is quickly heated and the steam arising therefrom passes into the condensing chamber, G. There it condenses and, because of coming in contact with the cold surfaces of the chamber and being condensed, 100 passes out the discharge, J. The fact of the condensing chamber being lined with lead renders the distilled water more adaptable for use for batteries than it otherwise would be. There being so little water in 105 the steamer it takes but a very few moments to obtain the steam, and the condensing chamber being so removed from anything connected with the fire or heating apparatus, its lower as well as its upper walls being 110 separated from metallic connection with the burner and provided with a large surface

in contact with the air, therefore condenses the steam quickly.

My apparatus is simple in its construction, it can be made very inexpensively and is 5 readily understood, requiring little attention, and is effective in operation.

What I claim as my invention and desire to secure by Letters Patent is:

10 An automatically-operated still comprising an air-tight container for undistilled water; a steamer of larger diameter than the container; a tube provided with a small bore connecting the bottom of the steamer with the bottom of the container; a pipe

connecting the top of the container with the lower part of the steamer; said steamer provided with converging walls; a stack projecting from the top of the converging walls; a condensing chamber with which the stack registers; and a cooling chamber adjacent to the condensing chamber, substantially as desired.

In testimony whereof I have affixed my signature in the presence of two witnesses.

GEORGE W. CRISPELL.

Witnesses:

FREDERICK W. CAMERON,
BEULAH CARLE.
